ARTHUR PENTECOST, OF NEW YORK, N. Y., ASSIGNOR TO WALES ADDING MACHINE COMPANY, OF WILKES-BARRE, PENNSYLVANIA, A CORPORATION OF PENNSYLVANIA.

ELIMINATING MECHANISM FOR CALCULATING MACHINES.

Application filed August 4, 1921. Serial No. 489,728.

To all whom it may concern:

Be it known that I, ARTHUR PENTECOST, a subject of the King of England, residing at New York city, New York County, New York, have invented new and useful Improvements in Eliminating Mechanism for Calculating Machines, of which the following is a specification.

The calculating machine art is replete with examples of means operated by tappets on the paper carriage, as the latter shifts from column to column, to set various mechanisms to effective position, so that upon the succeeding operation of the machine, the normal adding function of the machine will be eliminated, and the same mechanism is readily arranged to effect the operation of other means appertinent to calculating machines.

Sometimes, as in patent to Schuppe, #1, 308,117, July 1, 1919, means operated from the main drive shaft is employed to set to effective position, mechanism which eliminates or modifies the normal calculating and listing operations of the machine.

One object of the present invention is the provision of a novel controlling medium whereby to set the operation-modifying mechanism to effective position and to release the modifying mechanism to enable its restoration to idle position.

Another object is to simplify and improve the means to automatically control the operation-modifying mechanism, whereby to minimize the danger of getting out of order, as well as to reduce the number of parts, and thereby decrease the expense of manufacture.

A still further object is to provide selective means to automatically control the operation-modifying mechanism of a calculating machine, so arranged that such control may be exercised when the work sheet is brought to one or another of its positions as the paper carriage travels from column to column, the selective means being contrived to operate the modifying mechanism one or more times, as desired, in any single cross-tabulating travel of the carriage.

In effecting the foregoing and other objects, I utilize the customary spring drum employed to draw the carriage in one direc-

tion, as a driving means to actuate the mechanism which controls the operation-modifying device.

Other objects and advantages will be more fully set forth hereinafter and particularly pointed out in the claims.

In the accompanying drawings, Fig. 1 is a longitudinal sectional view through a Wales machine, showing one embodiment of my invention, applied thereto;

Fig. 2 is a detail plan view of the control mechanism associated with the spring drum or drive means, the parts being in normal idle position;

Fig. 3 is a similar view, showing the control mechanism in effective position;

Fig. 4 is a detail plan view of one form of adjustment applicable to the control mechanism, parts being removed; and

Fig. 5 is a similar view of a modified form of adjustment.

Although I have selected the Wales machine in connection with which to illustrate this embodiment of my invention, it is obvious that the invention is applicable to other machines as well.

The Wales mechanism is of the general type shown in U. S. patents to Wales #794- 80 205, July 11, 1905, and #797,032, August 15, 1905; McFarland #842,282, January 29, 1907, and #1,024,013, April 23, 1912; and Pentecost & Fisher #1,335,794, April 6, 1920, to which reference may be had for a more complete explanation of the construction, than that which follows.

A base 965 supports side frames 967 between which are mounted from front to rear successively, the keyboard, the accumulating 90 and the printing mechanisms.

The keys 117 of the keyboard, arranged in denominational rows, operate corresponding levers 116 to project stops 115, likewise arranged in denominational files, into the 95 paths of their corresponding denominational adding racks 310.

The adding racks 310 are pivotally supported by individual front and rear arms 312 and 311, respectively journaled on a cross shaft 300 and a cross rod 301. Springs 383 secured at their rear ends to the rear supporting arms 311, and at their front ends to a restraining and restoring bar 205 tend

to advance the racks towards their corresponding denominational files of stops 115.

The restraining and restoring bar 205 is carried by fingers 265^m depending from an oscillatory bar 265 extending between the side frames 967.

The usual Wales mechanism, not shown, operates through the bar 265 to normally retain the restraining and restoring bar 205

10 pressed against the front arms 312 to hold the adding racks 310 in their home positions against the tensions of their individual drive springs 383.

15 Depressing the keys 117 corresponding to the amount to be accumulated and printed, projects the appropriate stops 115 into the paths of the racks 310 corresponding denominational with the digits composing the amount. The stops 115, when projected, 20 displace rack-arresting detents 221 which normally lie in the paths of the racks 310.

25 A counter-supporting axle 400 extends across the machine above the racks 310, and denominational counters 490 are individually journaled on the axle, each counter being provided with a pinion 435 adapted to mesh with its corresponding rack 310, to enable the latter to turn the counters according to the distances through which the 30 racks travel in one direction.

Means well known in the Wales machine and not herein fully illustrated, normally supports the counter axle 400 so that the counters are disengaged from their racks.

35 Advancing the main drive shaft 200 on its forward stroke in any convenient manner, against the tension of the main restoring spring 285, operates the usual Wales mechanism, not shown, to rock the bar 265 40 and withdraw the restraining and restoring bar 205 from in front of the rack-supporting arms 312. The springs 383 advance the racks 310 until the latter are arrested by contact with the projected stops 115 or by 45 the detents 221 in those denominations wherein no keys have been depressed.

50 The main drive shaft 200, on its forward stroke, draws forwardly a link 214 connected to a counter-engaging and disengaging rod 303 mounted in radius arms 323 journaled on and depending from the cross shaft 300, to swing the rod 303 forwardly. This rod 303 controls the engagement and disengagement of the counters 490 and their racks 310 by 55 the customary Wales mechanism, not shown. As the main drive shaft 200 approaches the end of its forward stroke in an adding operation, it causes the rod 303 to trip the counter-supporting mechanism (not shown) 60 and thereby effect the engagement of the counters 490 with the racks 310, after the latter have completed their advance against the key-set stops 115 or the detents 221.

65 The main drive shaft is then released to enable the main spring 285 to restore the

parts to normal position. Accordingly, the rack-restraining and restoring bar 205, because of its connection (not shown) with the main drive shaft, presses against the front arms 312 to return the racks 310 to their 70 home positions. The advanced racks, during such restoration, turn their counters 490 to register thereon the amount corresponding to that set up on the keyboard.

Meanwhile, the counter-engaging and disengaging rod 303, under the influence of the links 214, is returning idly towards its normal position, and just prior to the end of its return travel, and after the restoration of the racks 310, it operates the well 80 known Wales linkage (not shown) to disengage the counters 490 and their pinions 435 from the racks 310.

85 Printing the amount set up on the keyboard is effected during the same operation that effects the accumulation of such amount on the counters. The rear rack-supporting arms 311 are equipped with rearwardly extending converging levers 311^m connected by links 515 with the denominational typebars 90 514. Types 561 are carried in typeheads at the upper ends of the typebars. As the racks 310 advance against the key-set stops 115, as above explained, the rear supporting arms 311 rock forwardly, and through the converging levers 311^m, and links 515, lift the typebars 514 to position the types 561 corresponding with the depressed keys, at the printing line, on a platen 2094. Normally cocked hammers 510 are tripped by suitable mechanism (not shown) prior to the restoration of the rack bars 310, the hammer striking firing pins 562^d to drive the latter against the positioned types 561, and impress them upon the work sheet. The 100 105 hammers 510 are reset to cocked position during the return stroke of the main drive shaft 200.

110 Should it be desired to print an amount without accumulating the same on the counters 490, all that is necessary is to prevent the engagement of the counters 490 and their pinions 435 with the racks 310.

115 Heretofore, this has been accomplished by providing a pair of retaining members in the form of hooks 417 depending from a cross shaft 404 journaled in the side frames 967, and normally held inactive by a spring 481. Depression of a key 419 mounted on an arm 421 fast on the cross shaft 404 turns 120 the shaft to rock the retaining hooks 417 beneath the counter axle 400, to hold the counter axle, and consequently, the counters 490 and their pinions 435, out of engagement with the racks 310, during the forward and 125 return strokes of the main drive shaft 200.

The spring 481 restores the retaining hooks 417 to their normal idle positions, upon the release of the key 419.

130 A platen axle 2004 on which the platen

2094 is mounted, is journaled in end frames 2010 secured to a carriage slide 2065 travelling between the rails 2067 forming a carriage bracket extending between and fastened 5 to the side frames 967. Shifting the slide 2065 between the rails positions one or another column on the work sheet at the printing point opposite the group of denominational type-carriers 514.

10 The carriage and platen are held where adjusted relatively to the printing point, by the releasable engagement of the teeth 2018^m of stops, with an abutment 2091^a fixed on one of the carriage rails 2067, reference being directed to the patent to Pentecost & Fisher, #1,335,794, for a more complete explanation of this mechanism. The stops are preferably adjustably mounted on a toothed bar 2092^b journaled in and extending between the end 15 frames 2010 of the carriage, and a spring 385 connected to the bar 2092^b, yieldingly retains the active stop tooth 2018^m in engagement with the abutment 2091^a. A finger lever 2022^a connected to the bar 2092^b, enables the operator to manually release the active stop tooth 2018^m from the abutment by rocking the bar 2092^b 20 counterclockwise against the tension of the spring 385.

Line spacing of the work sheet is automatically effected by a thrust bar 2026, the forward end of which is connected to a cross bar 302 mounted in and extending between the radius arms 323 which support the counter-engaging and disengaging bar 303.

35 The rear end of the thrust bar 2026 is provided with a foot 2026^m lying in front of the universal line space bail 2002 carried in the depending arms 2016^a whose upper ends are provided with trunnions 2053^b.

40 journaled in the end frames 2010.

A spring 2486 presses the universal line spacing bail 2002 against the foot 2026^m. A bell crank 2016, one end of which is fast on the adjacent trunnion 2053^b, carries the line space pawl 2014 pivotally mounted thereon, the pawl having a stud 2058^t adapted to contact the free arm of the bell crank. A spring 2082^a tends to hold the line spacing pawl 2014 in contact with a line space 45 ratchet 2020 fast with the platen.

The main drive shaft 200, on its forward stroke, advances the radius arms 323 and cross bar 302, which in turn, draws the thrust bar 2026 forwardly. Spring 2486 is 55 thus freed to cause the universal line space bail 2002 to follow the foot 2026^m of the thrust bar, to swing the supporting arms 2016^a forwardly and turn the trunnion 2053^b in a counterclockwise direction. The trunnion rocks the bell crank 2016 in the same direction to retract the line space pawl 2014 60 for a new bite on the ratchet 2020.

The main drive shaft, on its return stroke, forces the thrust bar 2026 rearwardly, 65 against the advanced line space bail 2002

to drive the pawl 2014 upwardly through the abovementioned train of mechanism and feed the work sheet.

Automatic tabulation of the carriage across the machine to bring successive 70 columns to the printing point, is conveniently effected by means of a trip member 2023^c pivotally mounted on an arm 2023^e fast on the trunnion 2053^b, in combination with a spring drum 2068, and the tape 2099 (Figs. 75 2 and 3) one end of which tape is connected to the spring drum and the opposite end of the tape to the carriage slide 2065 in the usual manner. A spring 582 (Fig. 1) connected to one end of the trip member 2023^c 80 tends to hold the nose at the other end of the trip member in position to contact a lip 2023^b secured to and depending from the tabulating stop bar 2092^b. At each operation of the drive shaft 200, the trunnion 2053^b 85 oscillates and rocks the arm 2023^e to wipe the nose of the trip member 2023^c past the lip 2023^b to thereby rock the tabulating bar 2092^b and disengage the active stop tooth 2018^m from the abutment 2091^a. Disengagement of the tooth 2018^m from the abutment, 90 frees the carriage to the action of the spring drum 2068, which draws the carriage leftwardly by means of the take 2099. Meanwhile the nose of the trip member 2023^c 95 escapes past the lip 2023^b, thereby enabling the spring 385 to restore the tabulating bar 2092^b with its stop teeth 2018^m to normal position, so that as the carriage, in its leftward travel, brings the next stop tooth 2018^m 100 to the abutment, the tooth can engage the abutment and detain the carriage with a new column at the printing point, until the tabulating bar 2092^b is again rocked.

An adjustable control member 2023^a determines whether or not the column tabulating mechanism or the line spacing mechanism shall be effective, all of which is fully explained in the patent to Pentecost & Fisher, above referred to.

The foregoing constitutes a part of the present invention only in so far as the various mechanisms are related to and cooperate with the novel features hereinafter set forth.

It has been shown that in cross-tabulating work the operator is relieved of the necessity of manually spacing the carriage from column to column.

In many tabulations, it is desired to print designating numbers, dates or the like, without accumulating them on the counters, and the completion of such tabulations is facilitated, and the operator's mind freed from the duty of remembering to manually operate the non-add key 419, if the non-add mechanism is arranged to be automatically shifted to effective position as the carriage brings the columns in which dates, designating numbers and the like are listed, to the printing point.

Heretofore, this has been accomplished in some instances, by arranging tappets on the carriage which, during the carriage travel, are brought into contact with mechanism set 5 by such engagement of the tappets, to an ineffective position, so that it will not operate to shift the counters into mesh with their racks.

In other words, the mechanism for effecting 10 the elimination of the adding operation, does not positively hold the counters against engagement with their racks, but instead, adjusts the usual counter-shifting mechanism, so that upon the operation of the machine, the mechanism will function idly, leaving the counters inactive.

In other cases, the non-add or other mechanism for eliminating or modifying the usual functions of the machine, is driven directly 20 from the main shaft.

The present invention aims to provide a novel controlling or driving device for a means adapted to positively affect a mechanism, the customary operation of which it 25 is desired to prevent or modify.

Accordingly, I have contrived to automatically control an eliminating mechanism directly from the spring barrel 2068, and have illustrated one application of my idea 30 in connection with the non-add mechanism, it being recognized that the invention is equally applicable to non-print mechanisms and other mechanisms affecting or modifying the normal accumulating and printing 35 operations of a calculating machine.

As one simple and convenient means to accomplish the automatic control of the non-add mechanism from the spring drum 2068, I provide a link 1 (Figs. 1-3) connected at 40 its forward end to one of the non-add or counter-retaining hooks 417, and at its rear end to the upturned end of a lever 2, pivotally mounted at 3 on the bracket 2011^a supporting the spring drum. The opposite end of the lever 2 may extend over the upper face of the spring drum 2068 and carries a flipper pawl or flexible tappet 4, (Figs. 2 and 3), the nose of which projects beyond the adjacent end of the lever. This tappet is 45 pivoted to the lever at 5, and a spring 6 connected to the tappet and to a stop 7 on the lever 2, normally holds the tail of the tappet against the stop 7 which arrests its travel in one direction.

An arm 8 (best shown in Fig. 4) loosely journaled on the hub 2068^m of the spring drum, carries a stud or actuator 9 near its outer end, the stud passing through the arm so that its projecting lower end may enter 50 between the teeth of a recessed or star wheel 1117 fixed to turn with the spring drum, to retain the arm and stud in place.

As the spring drum 2068 and star wheel 1117 turn, in feeding the paper carriage left- 55 wardly, the upper end of the stud 9 wipes

along the nose of the tappet 4 in a counter-clockwise direction, (viewing Figs. 2 and 3) to actuate the lever 2 and force the link 1 forwardly, to shift the retaining members 417 to effective position against the tension 70 of their restoring spring 481. The actuating stud 9 is so positioned relatively to the lever 2, that it remains in contact with the nose of the flexible tappet 4 while the carriage is in any predetermined or selected columnar 75 position, and continues to hold the eliminating mechanism effective until the spring drum operates to feed the carriage to the next column, whereupon the stud 9 escapes past the nose of the flexible tappet 4 and enables the spring 481 to restore the eliminating 80 mechanism to idle position.

Adjustment of the arm 8 and actuator 9 relatively to the spring drum or drive means 2068, to enable the operator to select the column 85 wherein the printed amounts shall not be accumulated, may be conveniently effected in the manner disclosed most clearly in Fig. 4. The arm 8 is slotted, as at 10, to embrace the hub 2068^m of the spring drum 2068, 90 and may be provided with a spring-pressed plunger 11 seated in the arm, the head of the plunger extending into the slot 10 in the arm and bearing against the hub 2068^m to hold the arm 8 at one limit of its travel, with 95 the lower end of the actuating stud 9 entered in one of the recesses of the star wheel 1117, to lock the arm and stud where adjusted.

To vary the adjustment, whereby to effect 100 the automatic setting of the eliminating mechanism when the paper carriage brings another column to the printing line, the operator grasps the actuating stud 9 and draws the arm 8 radially outwardly against the influence of the spring-pressed plunger 11 until the lower end of the stud or actuator 9 is withdrawn from the recess in the star wheel, after which the arm 8 may be rotated on the hub to another position and released, whereupon the spring-pressed plunger 11 draws the arm radially inwardly to seat the lower 105 end of the stud 9 in the adjacent recess in the star wheel 1117.

Furthermore, the hub 2068^m may carry a 110 plurality of arms 8 and studs 9 superposed one above the other, as shown in Figs. 1, 2 and 3, to effect the setting of the eliminating mechanism two or more times during a single cross-tabulating journey of the carriage.

I have illustrated in Fig. 5 a simple modification of the actuator for the lever 2. Referring to said figure, the top plate of the drum 2068 may be provided with a circular row of apertures 12, in any of which may 115 be inserted a threaded stud 13. The tappet 4 overlies the circular row of apertures so that as the drum rotates, the actuating stud or studs 13 will be brought to contact with the tappet 4 and operate the lever 2.

This contrivance lends itself readily to the purpose to which it is applied in this specification.

The peripheral contour of the drum 2068 is such that in drawing paper carriages of the ordinary length, say thirteen inches, from beginning to end of a line, the drum will turn about one and one-quarter times.

Assuming that there is provided but a single tripping stud 9, it is obvious that it may be so positioned on the drum 2068 as to engage the flipper pawl or tappet 4, when the carriage is in any of its positions.

Thus, the trip 9 may be so located as to engage the tappet 4 when the carriage has positioned the paper at the beginning of a line, as in listing check or other designating numbers not to be added, and amounts designated by such numbers, which amounts are to be added, thus—

1273 ▽	23.50 ⊖
1274 ▽	47.85
1275 ▽	9.21

the first column of figures being non-added as indicated by the sign, and the second column being added.

Or the use of two studs 9 properly located, will operate the non-add mechanism twice in the rotation of the spring drum 2068 as the carriage travels from beginning to end of a line, as in the following example:

Agency No.	Risk No.	Amounts.
275 ▽	14,284 ▽	21.72 ⊖
276 ▽	18,725 ▽	33.00
277 ▽	9,432 ▽	42.19

wherein numbers printed in the first two columns are non-added.

It will be seen at once that the passage of a trip 9 past the tappet 4 as the spring drum shifts the paper carriage from column to column will merely operate the non-add mechanism idly, and as soon as the trip releases the tappet, the spring 481 retracts the non-add mechanism to ineffective position, and that it is only when the trip 9 remains in contact with the tappet 4 while the paper carriage is at rest that the non-add mechanism is retained effective.

With longer carriages designed to accommodate sheets of greater width, the spring drum may be equipped with a larger number of trips 9.

When the form of trip illustrated in Figure 5 is used, the removal of all trips entirely prevents the possibility of effecting an operation of the non-add mechanism automatically, and with either form shown, if the tripping studs are so located as to be out of contact with the tappet 4 whenever the paper carriage is at rest in any of its columnar positions, the non-add mechanism remains idle.

Other changes may be made in the form

and arrangement of the several parts described without departing from the spirit and scope of this invention.

What I claim as new, is:—

1. In a calculating machine normally adapted to accumulate and print amounts, the combination with a traveling carriage; a rotatable drive means to draw the carriage; and settable means to change the normal operation of the machine; of means directly controlled by the drive means to automatically adjust the settable means to effective position.

2. In a calculating machine, the combination with a traveling carriage; a rotatable spring drum to draw the carriage in one direction; and mechanism settable to effective position to modify the normal operation of the machine; of means directly controlled by the spring drum to automatically shift the operation-modifying mechanism to effective position.

3. In a calculating machine, the combination with a traveling carriage; a spring drum to draw the carriage in one direction to enable a line of amounts to be printed across the work sheet; and means to modify the normal operation of the machine; of a train of mechanism to actuate the operation-modifying mechanism, such train of mechanism including a lever; and an actuator mounted on and traveling with the spring drum, to shift the lever as the spring drum, in its rotation, brings the actuator adjacent the lever.

4. In a calculating machine, the combination with a traveling carriage; a spring drum to draw the carriage in one direction to enable a line of amounts to be printed across the work sheet; and means to modify the normal operation of the machine; of a train of mechanism to actuate the operation-modifying mechanism, such train of mechanism including a lever; a flexible tappet mounted thereon; and an actuator mounted on and traveling with the spring drum, to contact the tappet and shift the lever as the spring drum, in its rotation, brings the actuator adjacent the tappet.

5. In a calculating machine, the combination with a traveling carriage; a spring drum to draw the carriage in one direction to enable a line of amounts to be printed across the work sheet; and means to modify the normal operation of the machine; of a train of mechanism to actuate the operation-modifying mechanism, such train of mechanism including a lever; a flexible tappet mounted thereon; and a stud carried by and adjustable to different positions around the spring drum, to contact the tappet and shift the lever as the spring drum, in its rotation, brings the actuator adjacent the tappet.

6. In a calculating machine, the combination with a traveling carriage; a spring

drum to draw the carriage in one direction to enable a line of amounts to be printed across the work sheet; and means to modify the normal operation of the machine; of a 5 train of mechanism to actuate the operation-modifying mechanism, such train of mechanism including a lever; a flexible tappet mounted thereon; and a stud carried by and adjustable to different positions around the 10 spring drum, to contact the tappet and shift the lever as the spring drum, in its rotation, brings the actuator adjacent the tappet.

7. In a calculating machine, the combination with a traveling carriage; a spring 15 drum to draw the carriage in one direction to enable amounts to be printed in a line across the work sheet; and non-add mechanism to prevent accumulation of printed

amounts; of an actuator carried by and traveling with the spring drum; a lever; a 20 link to transmit movement of the lever to the non-add mechanism; and a flexible tappet mounted on the lever and extending into the path of the actuator to be struck thereby, and operate the lever, as the actuator 25 travels in one direction.

8. In a calculating machine, the combination with a traveling carriage, a prime mover to shift the carriage step by step in cross tabulating direction, and settable 30 means to vary the normal operation of the machine; of actuating mechanism controlled and operated directly by the prime mover to automatically adjust the settable means to effective position.

ARTHUR PENTECOST.
